UNITED STATES PATENT OFFICE.

WILLIAM JNO. H. BOOHER, OF OXFORD, NORTH CAROLINA.

DESIGN FOR A POISON-BOTTLE.

42,831.

Specification for Design.

Patented July 23, 1912.

Application filed February 10, 1912. Serial No. 676,830. Term of patent 14 years.

To all whom it may concern:

Be it known that I, WILLIAM JOHN H. BOOHER, a citizen of the United States, residing at Oxford, in the county of Granville and State of North Carolina, have invented a new, original, and ornamental Design for Poison-Bottles, of which the following is a specification, reference being had to the accompanying drawing, forming part thereof.

The figure is a perspective view of a poison bottle showing my new design.

I claim:

The ornamental design for a poison bottle, as shown.

W. JNO. H. BOOHER.

Witnesses:

W. T. YANCEY,
JNO. BUCHANAN.
